LUMINOUS SIGN

Peter A. Gadomski, South Bend, Ind.

Application January 5, 1949, Serial No. 69,290

1 Claim. (Cl. 40—142)

1

This invention relates to improvements in luminous signs.

The primary object of the invention is to provide a sign composed of characters formed of plastic, translucent and luminous material, constructed with marginal portions having the property of increasing light emission compared to the light emission occurring at the remaining portions thereof, whereby the character presents a striking and attention-attracting appearance.

A further object is to provide a sign character formed of translucent plastic sheet material having fluorescent material incorporated therein, wherein the marginal portions of said character are bent angularly forwardly to expose the edges thereof to view, said character having the property of collecting ambient light and emitting the same in greater concentration at said exposed edges than at the remaining portions of said character.

A further object is to provide a luminous sign which is simple in construction, whose characters may be assembled in any desired relation by the user and said relation changed quickly and at will, which has a novel mounting, and which is rendered luminous by ambient light as well as by illuminating means associated therewith.

A further object is to provide a sign composed of a plurality of individual rigid sign characters, each having a mounting member secured at an edge thereof to extend alongside the character and adapted to have a resilient detachable locking engagement in an elongated groove or socket in a carrier or supporting member.

Other objects will be apparent from the following specification.

In the drawing:

Fig. 1 is a face view illustrating one embodiment of the invention.

Fig. 2 is a vertical sectional view taken on line 2—2 of Fig. 1.

Fig. 3 is a front perspective view of a sign character.

Fig. 4 is a fragmentary perspective view of an alternative construction with parts shown in section.

Fig. 5 is a fragmentary perspective view of another alternative construction of a sign.

Referring to the drawing which illustrates the preferred embodiment of the invention, and particularly to Figs. 1 to 3 thereof, the numeral 10 designates sign characters adapted to be used in making up a sign for advertising and other purposes. The characters 10 may be formed in a wide variety of sizes and shapes and may represent letters, numerals and other indicia. Each

2

of these characters is preferably formed of rigid plastic sheet material, and preferably formed of synthetic resins, such as acrylic, cellulose acetate, styrene or the like. The material of which the characters are formed is translucent and may be transparent. Also, the material may be plain or colored. Where colored, the pigmentation should not be sufficient to destroy the translucency thereof. The plastic material is of a character having fluorescent material distributed uniformly therethrough in the manner well understood in the art, so that the material has at least some measure of luminosity when viewed in ambient light conditions as well as in artificially illuminated conditions. Each character has a flat web portion 12 and marginal portions 14 bounding the portion 12 at all edges thereof, the portions 14 being of increased thickness in a direction perpendicular to the plane of the web 12 and projecting forwardly from the front surface of said web. In other words, the character is constructed of dished or recessed cross-sectional configuration with the concavity facing forwardly. The characters 10 may be formed in any suitable manner as by molding, reshaping flat sheet material, or the like. Where the character is formed from flat sheet material, the marginal portions 14 will be of substantially the same thickness as the plate portion 12, but this condition is not essential and said marginal portions may be thicker or thinner than the base 10. The front edges 16 of the portions 14 of each character preferably lie substantially in a common plane forwardly offset from the plane of the front face of the web or base 12 and substantially parallel thereto.

Each of the characters 10 has a mounting member 18 secured thereto. In the preferred embodiment of the invention, the mounting member 18 is formed of channel-shape having a base 20 and a pair of flanges 22. The mounting member 18 is preferably formed of plastic sheet material and is of greater length than width. The base 20 of each mounting member is preferably cemented, bonded or otherwise secured to the edge of the character 10 to extend alongside the edge of that character and lie in substantially the same plane as the character. The flanges 22 project outwardly from the character. The mounting member 18 may be positioned in any desired relation with respect to the characters 10, as at the bottom thereof, as illustrated at 18 in Fig. 1, or at the top thereof as illustrated at 18 in Fig. 1, or along a side thereof. The mounting members 18 will preferably be substantially co-extensive with the dimension of the letter at the

edge to which the same is secured, and may be bonded thereto at one or more points. Thus it will be observed with respect to the characters M, A and U, shown in Fig. 1, the mounting members are secured at two spaced points. The characters T and R of Fig. 1, and I of Fig. 3, have the member 18 bonded thereto at only one point. Where that point is restricted, as in the case of the characters T and I, the mounting member 18 is of greater length than the width of the character. In instances where the member 18 is bonded to the curved portion of a character, as shown at Fig. 1 with reference to the character G, the member 18 will extend tangentially and will be of substantially greater length than the extent of the tangential engagement with the character. The cross-sectional configuration of the mounting member 18 may vary but the construction illustrated in Fig. 3 is preferred, in which it will be observed that each of the webs 22 of the channel is curved inwardly, thereby providing a reduced spacing therebetween at their center portions compared to the spacing therebetween at the base and at the mouth of the channel. The flanges or legs 22 of the mounting member 18 preferably have a certain amount of resilience. While each character 10 is illustrated as provided with one long mounting member, a plurality of short spaced aligned members 18, secured to different parts of one side of the character may be provided.

In the form of the device illustrated herein, the mounting member 18 is of substantially the same width as the thickness or depth of the character 10. It will be understood, however, that this relation is not critical and that the width of said member may be greater or less than the depth of the character 10, although in cases where the width of the member 18 is greater than the depth of the character 10, it is preferred that the front face of the member 18 extend substantially flush with the front edges 16 of the character. In some instances it may be desirable to have the member 18 offset rearwardly so that its front surface is positioned rearwardly of the plane of the front edge 16 of the character.

In the use of the characters to form a sign, the mounting members 18 are mounted in an elongated groove in a supporting or carrier member, so positioned that the characters will be spaced from any surface which forms the background therefor. In other words, except for the engagement of the sign characters with the mounting members 18 to which they are secured, the characters 10 will be spaced from all surfaces or members, whereby light may strike all surfaces thereof, and particularly the back surface thereof. One form of such mounting is illustrated in Figs. 1 and 2, wherein a carrier 30 of substantially H-shape in cross-section is secured to a block or spacer 32 mounted upon a building wall or other support 34. The H-shape of the carrier 30 is illustrative, and it will be understood that said carrier may be of U-shape if desired. Where the H-shaped member is employed, two lines of sign characters, positioned respectively above and below the member 30, may be utilized. The member 30 provides one or more channels within which the mounting members 18 fit snugly and solidly to provide a firm support for the characters 10. It is preferred that the cross-sectional configuration of each of these channels shall substantially conform with the cross-sectional configuration of the mounting members 18 to provide a spring locked detachable fit of the

members 18 therein. In other words, if the member 18 has its channel legs 22 curved or configured as shown, the side walls of the receiving groove or channel of the member 30 will be similarly curved so that the mounting legs 22 must be sprung or flexed to insert them in the receiving grooves or channel of the member 30 and to remove them from said channel. This is particularly important in cases where the mounting member 30 is not positioned horizontally or where the channel or groove of a horizontal mounting member opens downwardly. The spring locked fit will thus serve to hold the characters against displacement from desired position and against release.

If desired, light-emitting means may be utilized with the sign. Thus, as illustrated in Fig. 2, brackets 36 may be mounted by the spacer 32 or by the wall support 34 to position and support light-emitting means, such as neon or fluorescent light tubes 38 between the wall or support 34 and the rear faces of the characters 10.

Signs formed or constructed in the manner disclosed and illustrated are particularly attractive and are characterized by an outline of each of the sign characters at the edges 16 thereof whose luminous properties are much greater than the luminous properties of the remainder of the character 10. Thus each character is sharply outlined and a two-tone or differential value light transmission effect occurs at each character. The effect is readily observable at all times and regardless of lighting conditions as long as sufficient light exists around the character to render the same visible. In other words, the marginal portions 14 of the character have the property of collecting and concentrating light in substantially greater measure than the base or plate portions 12 of the characters, and the character is visible and will attract attention under conditions in which a plane or flat character formed of the same material would be inconspicuous. The forward projection of the flanges 14 is of critical importance to produce this effect. The positioning of the character with a similar flange or thickened portion projecting rearwardly possesses this property, if at all, only to very limited and substantially reduced value or extent, and not sufficient to be noticed or to attract attention. The forward projection of the flanges or margins 14 has a property somewhat similar to a lens in collecting and concentrating light at its edge 16 to produce the distinctive character outlining functions described.

The characters 10 are rigid and will maintain their desired position when the mounting member 18 is inserted in a channel or groove of a support and, where mounted spaced from a wall or support 34, each individual character stands out distinctly, and a sign formed from the characters has a three-dimensional appearance. The use of light emission means, such as the neon or fluorescent tubes 38, increases the luminosity of the characters, and, in cases where colors are involved, either with respect to color of the light or the color of the material from which the character is formed, or both, it is possible to increase the attention-attracting properties or qualities of the sign. The sign may be used either in interior or exterior locations. Where used exteriorly, mechanical anchoring or fastening means, preferably of detachable character, may be used between the mounting member 18 and the support therefor, said securing means being of any character found suitable to insure

maintenance of the position of the sign characters and to withstand dislocating stresses, such as wind stresses.

A modified embodiment of the invention is illustrated in Fig. 4. In this construction a different form of mounting is employed, the same preferably constituting a metal plate 40 having a rear flange 42 provided with holes or openings 44 to receive securing means for attaching the same to a wall or supporting surface 34. An up-standing web 46 is carried by an intermediate portion of the plate 40 spaced forwardly from the flange 42 and defining the rear wall of a channel or groove whose front wall is defined by a second upwardly projecting flange 48 also spaced rearwardly from the front edge of the member 40. A front flange 50 projects upwardly and cooperates with the web 46 to define the channel within which the mounting member 18 of the sign character 10 is received. The channel defined by the base 40 and the flanges 46 and 48 is adapted to receive an elongated rigid translucent panel 52 which forms a background for the characters 10. This panel 52 may be formed of frosted glass, translucent but not transparent plastic, or any other material found suitable. A neon or fluorescent tube 54 is mounted upon brackets 56 secured to and projecting from the flanges 48, the light-emitting tube 54 preferably being positioned at a level substantially centrally with respect to the vertical dimensions of the sign characters 10. The bracket will so position the tube 54 that said tube is spaced rearwardly from the panel 52 and is spaced forwardly from the wall or support 34 which is engaged by the flange 42.

This construction possesses the same advantages as the construction previously described, but provides additional advantages of a prefabricated unitary member which can be mounted upon a support quickly and rapidly, which has a built-in support for the light-emitting means, and which has the light-diffusing panel 52. The same advantages of the previously mentioned construction, with respect to the ready mounting of the sign characters 10 in selected arrangement and the removability thereof for replacement and rearrangement, is also possessed by this device. The width of the base plate 40 of this construction adapts it for mounting upon a horizontal support as an alternative to securing thereof to a vertical support, as will be obvious. Furthermore, the self-contained character of the device renders the device portable, providing that the electrical connections (not shown) for the lamp circuit are detachable, and provided further that arrangements are made for the connection in such circuit of transformers and other electrical components required in a tube operating circuit.

A further modified embodiment of the invention is illustrated in Fig. 5, wherein an elongated housing is provided, having a back wall 60, a top wall 62 and a bottom wall 64. The front of the housing is open, and flanges or stops 66 at the

forward end of the top wall and 68 upon the bottom wall form abutments against which a translucent front closure panel 70 may bear. A suitable detachable latching member 72 may be provided to engage the upper margin of the panel 70 and to detachably anchor the same to the casing, as at its top wall 62. The bottom wall 64 of the casing may project forwardly from the stop 66 to form a support upon which the panel 70 may bear, and terminates in an upturned flange 74 at its front end. The spacing between the panel 70 and the flange 74 defines a channel into which the mounting members 18 of sign characters 10 may be inserted. The dimensions of the parts are such that the translucent panel 70 projects above the top of the sign characters 10. Any suitable light-emitting means, such as lamps 76, may be mounted in sockets 78 supported by the base 64 rearwardly of the panels 70.

This device may be provided with means for securing the rear wall 60 of the casing to a wall or other vertical support 34. Alternatively, the unit may be made portable and is adapted to rest flat upon a horizontal supporting surface.

The light from the light source 76 is diffused through the panel 70 to illuminate the character 10 whose flanges 14 concentrate that light and emit it in strongest concentration at the edges 16 of the character or characters.

While the preferred embodiments of the invention have been illustrated and described herein, it will be understood that the construction of the device may be altered within the scope of the appended claim without departing from the spirit of the invention.

I claim:

A sign comprising an elongated rigid carrier having a longitudinal groove, a sign character formed of translucent plastic material having a shape representing an indicia and forwardly projecting marginal flanges, and a rigid elongated mounting member secured to one of said flanges and extending alongside and in substantially the same plane as said character, said mounting member having a snug detachable fit in said groove, said carrier and mounting member both being of channel shape in cross-section and said mounting member being resilient, said channel members both having opposed inwardly curved side walls defining reduced dimension portions intermediate the mouth and the base of said channels.

PETER A. GADOMSKI.
